Crown Office

UNITED STATES PATENT OFFICE.

ARNO WETZEL, OF MILWAUKEE, WISCONSIN.

YARN-TENSIONING DEVICE.

Application filed October 30, 1926. Serial No. 145,224.

This invention relates to yarn tensioning devices, and is particularly directed to yarn tensioning devices adapted for use on knitting machines.

5 In the yarn tensioning devices heretofore constructed for knitting machines, one very common form is that of a wick carried by a transverse bar on the machine and over which the thread or yarn passes. The 10 thread rubs against the wick and thus secures the desired tension. These devices have been found to give considerable trouble due to the rapid wearing of the wick and consequently its irregular action and short life.

15 This invention is designed to overcome the defects noted above and objects of such invention are to provide a novel form of yarn tensioning device which may be clipped on to the usual transverse bar found on knitting 20 machines and which does not have the wear and short life of the usual types of devices, such as discussed above, and which lasts indefinitely, and which applies in an automatic manner the requisite tension upon the 25 thread in a smooth and even manner.

Further objects are to provide a device which is extremely simple in construction, which will correctly guide one, two, or more threads as needed, and apply tension individually to these threads in the proper amount.

An embodiment of the invention is shown in the accompanying drawings in which—

Figure 1 is an end view of the device 35 showing the supporting bar in section;

Figure 2 is a view from the rear side;

Figure 3 is a view from the front side.

Referring to the drawings, it will be seen that the transverse bar 1 is of rectangular 40 contour and supports the tensioning device. This tensioning device is made preferably of sheet metal and has an upper rounded portion 2 which fits over the upper portion of the bar and rests thereon. From this 45 rounded portion, a pair of downwardly extending arms 3 projects. These arms are upturned as indicated at 4 and 5 on the front and rear sides of the device and are spaced from the rounded portion 2 and from 50 the arms 3, as shown most clearly in Figure 1.

The arm 4 carries a single porcelain eyelet 6 while the arm 5 carries a pair of porcelain eyelets 7. Obviously, if desired, more eyelets could be provided.

55 Adjacent each of the eyelets the sheet

metal is outwardly struck, as indicated at 8, and the outwardly bent arms 9 of wire levers or weighting members, are pivotally carried beneath these outwardly struck portions. These wire levers consist of looped body 60 portions 10 which are further looped or twisted to form an eyelet 11 at their extreme ends. The construction of these wire loops or levers is identical for the front and rear of the device except that in the form shown 65 two are employed on the rear arm 5, whereas as one only is employed on the front arm 4.

The thread 13 is lead upwardly from the supply through the eyelets 11 of the rear levers or weighting members 10, through the 70 porcelain eyelets 7, over the rounded upper portion 2, through the front porcelain eyelet 6, and through the eyelet 11 of the front lever or weighting member.

If two threads are used, they are combined 75 or employed in the manner shown in Figures 2 and 3, from which it will be seen that the threads are individually tensioned and pass over the rounded portion 2 and thence outwardly through the eyelet 6 of porcelain 80 and through the eyelet 11 of the front lever.

The levers 10 place a slight tension on each 85 of the threads and causes them to bind or bear against the rounded portion 2 with a uniform pressure, thus producing the necessary frictional drag or tension.

Any little irregularity in the rate of feed of the thread or variations of this type is compensated for by the swinging motion of the levers 10 so that sudden tension can 90 not be placed upon the thread.

The rounded portion of the metal member is smooth and does not cut or injure the thread in any manner and, consequently, provides a surface over which the threads 95 may pass while they are held down against the surface by the action of the levers.

It will be seen, therefore, that applicant has provided a very simple yarn tensioning device particularly adapted for knitting machines or others of this type, which may be readily slipped over a supporting member, and which will thereafter automatically hold itself in place by the inherent springiness of its gripping arms.

It will be seen further that the device provides for taking up a certain amount of slack in the thread however rapidly this slack may be formed or varied in the action of the machine and further it will be seen that 110

the tension imposed upon the thread is of a uniform nature exactly suited to the needs of the machine.

It will be seen further that the device may be very cheaply made and readily applied.

Although the invention has been described in considerable detail, such description is intended as illustrative rather than limiting as the invention may be variously embodied 10 and as the scope of such invention is to be determined as claimed.

I claim:

1. A yarn tensioning device comprising a pair of arms adapted for positioning on 15 opposite sides of a support, said arms being connected by an upper portion over which the yarn is adapted to pass, said arms having outwardly extending parts provided with eyelets through which the thread is 20 passed, and having weighting levers pivotally mounted on the outwardly extending portions and bearing against said thread to hold said thread against the upper portion with a predetermined amount of pressure.
2. A yarn tensioning device comprising a 25 sheet metal member having a rounded upper portion provided with downwardly extending gripping arms, said gripping arms having outwardly projecting arms, eyelets carried by said outwardly extending arms, small levers pivotally carried by said out-

wardly extending arms and having eyelets in their outer ends.

3. A yarn tensioning device adapted to grip a supporting member, comprising a sheet metal structure having a rounded upper portion adapted for positioning over the supporting member and having downwardly extending spring arms adapted to grip opposite sides of the supporting member, said 40 spring arms continuing outwardly and carrying porcelain eyelets through which the thread is passed, and U-shaped levers having outwardly turned trunnions pivotally carried by the arms and having eyelets at 45 their free ends through which the thread is passed.

4. A yarn tensioning device comprising a member adapted to be carried by a support and having a smooth bearing face for the 50 thread, said member having a pair of stationary eyelets through which the thread is passed and located on opposite sides of the bearing face, and levers pivotally carried by said member and adapted to press 55 against said yarn to cause the yarn to slightly bind against the smooth bearing face.

In testimony that I claim the foregoing I have hereunto set my hand at Milwaukee, in the county of Milwaukee and State of Wisconsin.

ARNO WETZEL.
